TRUCK ILLUMINATING LAMPS
Floyd E. Kemp, 155 Asbury St., Evanston, Ill.
Filed Aug. 5, 1960, Ser. No. 47,722
4 Claims. (Cl. 240—52.15)

My invention relates to trucks which are loaded and unloaded on freight docks, and more particularly to the lamps employed for illuminating the interior of the trucks. This type of lamp is carried by a cord which leads from the ceiling of the dock. When the rear doors of the truck have been opened, the conventional lamp is hooked or otherwise temporarily attached over the entrance, so that the interior of the truck is illuminated while loading or unloading is going on. However, at times the driver of the truck forgets to detach the lamp when he drives away from the dock, in which event the cord is broken and the lamp is carried away by the truck.

In view of the above disadvantage, it is one object of the present invention to provide a lamp which becomes detached from the truck automatically and without damage or other impairment in case the truck is driven away from the dock while carrying the lamp.

A further object is to employ a magnetic mounting device for the lamp which is attachable to the top of the truck over the rear entrance by simple application.

Another object is to employ an electromagnet as the attaching device for the lamp, and include the electromagnet in the wiring circuit of the lamp.

An additional object is to provide a holder for the lamp which incorporates a switch in the electromagnet circuit and means to open the switch and extinguish the lamp in case the truck departs from the dock and pulls on the cord, the electromagnet releasing its hold in such event and causing the lamp to drop away from the truck.

Another object is to construct the novel lamp as a compact unit, and along lines of simplicity.

A better understanding of the invention may be gained by reference to the accompanying drawing, in which—

FIG. 1 is a fragmental rear view of the truck body, showing the lamp attached to the same;

FIG. 2 is a section on the line 2—2 of FIG. 1;

FIG. 3 is an enlarged section on the line 3—3 of FIG. 2, showing the switch open;

FIG. 4 is a view similar to FIG. 3, showing the switch closed; and

FIGS. 5 and 6 are, respectively, sections on the lines 5—5 and 6—6 of FIG. 3.

Referring specifically to the drawings, 10 denotes a typical truck body, with side doors 11 hinged to the same at 12 and shown folded back. The metallic rear edge of the body top is indicated at 13.

The ceiling or overhead support of the dock in which the truck is loaded or unloaded is indicated at 15, with an electric outlet fixture 17 installed. A cord 18 depends from the fixture to terminate with the usual lamp designed to provide illumination for the interior of the truck while it is in the dock. When the lamp is not in use, it simply hangs from the fixture to a point where it may be reached from the rear of the truck.

For the present purpose the cord 18 does not lead to the lamp directly, but through the intermediary of a lamp holder or attaching unit 20. Primarily this unit is in the form of a horizontally-positionable tubular housing made in lower and upper halves 20 and 21 which are secured together by side lugs 22, bolted at 23. The housing carries a pendent vertical spool 25, having an end flange indicated at 25a; and the cord—if found too long—is designed to be wrapped around the spool before entering the housing 20, as shown in FIGS. 1 and 3. FIGS. 2 and 4 show that a bracket 27 extends laterally from the lower end of

2

the spool 25 into the truck interior, the bracket carrying the lamp 30. A passage is provided through the spool and bracket for a cord 32 which supplies electric current to the lamp.

5 The housing 20 contains a switch interposed between the cords 18 and 32. Thus, one terminal of this switch receives the feed wires 18a of the cord 18 in the contact posts 35a of a companion pair of curved blades 35. These bear against an insulation block 37 which is slidable in the rear end of the housing 20, the inner end of the block having hollows 37a to seat the blades, and a partition 37b to separate them. The block also has longitudinal top and bottom grooves 37c receiving housing ribs 20a for sliding guidance and to keep the block from turning.

10 15 In the forward end portion of the housing is lodged a partition disc 40 extended with a central boss 40a. To the latter are applied the end portions of a companion pair of spring loops 42 which are in registration with the curved blades 35. Thus, when the block 37 is pushed inwardly, it will arch the blades until they meet the loops 42; and the further advance of the block will wrap the blades over the loops and compress the latter to the bulging form illustrated in FIG. 4.

20 25 Before the cord enters the housing 20, it descends through a keeper 45 behind the switch block 37. The latter has a latch 47 hinged horizontally at 47a and poised apart from the cord 18 when the lamp is not in use and the switch block 37 is in the backed position indicated in FIG. 3; and the tension of the blades 35 normally maintains the switch block in the backed position, which is an indication that the switch is open.

30 35 When the device is to be applied to a truck, the first concern is of course to light the lamp. To do this, the latch 47 is swung down to the horizontal position indicated in FIG. 4. The length of the latch first causes it to bear rearwardly on the cord 18 and seat the same firmly in the rear end of a keeper 45; and the action of the latch also causes it to bear forwardly on the switch block 37, to the extent of closing the switch as shown in FIG. 4. The switch connects with the wires 32a of the cord 32 by way of the terminals 42a of the loops 42, and the lamp therefore becomes lighted by the action just described.

40 45 The housing carries an electromagnet 50 in its front end, the core 50a of which may project as shown. The terminals of the electromagnet are shown at 50b, and connection between them and the terminals 42a is made by spring contact strips 52 carried by the disc 40, or other suitable means, whereby to include the electromagnet in the lamp circuit. Now the device is ready for application with the electromagnet core 50a to the metallic top edge 13 of the truck as indicated in FIG. 2, so that the lamp is supported to illuminate the interior of the truck.

50 55 When the work in the truck is ended, it is only necessary to open the latch 47 in order to extinguish the lamp and de-energize the electromagnet. The device will now drop away from the truck and remain suspended from the fixture 17 until its use is again required. However, should the driver or truck attendant neglect to open the latch, but drive off with the truck, the pull on the cord 18 will be upward in relation to the latch 47 and keeper 45, so that the cord will open the latch. The relaxation of the blades 35 will now open the switch in the housing 20, causing the lamp to become extinguished and the electromagnet to release its hold, so that the device drops away from the truck to the suspended or idle position mentioned.

60 65 By making the housing in upper and lower halves, it will be possible to assemble its contents with facility; and the disc 40 and electromagnet 50 may be locked in place by being formed with peripheral pockets 40c and 50c which receive lugs 20d carried by the walls of the housing.

70 It will now be apparent that the present device accomplishes the mounting of the lamp in the truck with an

automatic detaching factor. Normally, the device would be detached manually when the truck is about to be driven away; or, where it is necessary to close the doors of the truck before leaving, the position of the device is an obstacle to the closing of the doors and therefore dictates the manual removal of the device before the doors are closed. However, where the truck has been emptied or has few contents, the closing of the doors may be considered unnecessary and the removal of the device neglected or overlooked, in which event the automatic detaching feature would accomplish the removal of the device and the extinguishing of the lamp without damage to or loss of any part. The cord 18 should be made of ample length in case the truck is located at a distance from the outlet fixture 17. However, where the truck is nearby or directly underneath, the slack in the cord may be taken up by wrapping it on the spool 25, so that no part of the cord will hang in back of the truck entrance to be in the way. Further, the exposed position of the device and its liability to impact with the truck or objects being moved in or out of the same would disqualify the use of a conventional switch, whereas a strong pressing and wrapping engagement is secured in the present switch which should enable it to withstand shocks and vibration; and the fully enclosed position of the switch should protect it against corrosion from climatic conditions.

While I have described the invention along specific lines, various minor changes or refinements may be made therein without departing from its principle, and I reserve the right to employ all such changes and refinements as may come within the scope and spirit of the appended claims.

I claim:

1. An automatically operating switch-and-lamp holder for use on a magnetically attractive support surface comprising in combination an electric current conducting cord; a hollow housing including electromagnet means for engagement on said magnetically attractive support surface; said housing including cord-keeper means extending about an intermediate portion of

said cord; said housing including therein a normally open switch, said switch including a first contact means electrically connected to said electromagnet means; an electrically energized lamp carried by said housing and electrically connected to said first contact means for simultaneous energization with said electromagnet means; said switch including a switch block displaceably supported in said housing in opposition to said cord-keeper means; said switch including a biasing-contact means electrically connected to said cord and normally spaced from said first contact means engaging said switch block and normally urging the block toward said cord-keeper means; said switch block including a latch movably mounted thereon and clampingly engageable with said cord adjacent and against said cord-keeper means in opposition to said biasing-contact means for urging said block and biasing-contact means toward said first contact means for closing a circuit therebetween and simultaneously energizing said electromagnet means and said lamp.

2. The structure of claim 1 wherein said housing includes a depending spool and bracket supporting said lamp, said lamp electrical connection including a current conductor threaded in said spool and bracket and electrically connected to said first contact means.

3. The structure of claim 1 wherein said first contact means comprises a U-shaped leaf spring extending toward said switch block, said biasing-contact means comprising an arcuate leaf spring disposed in confronting relation to said U-shaped leaf spring, said switch block including an arcuate groove slidably receiving said arcuate leaf spring.

4. The structure of claim 1 wherein said latch comprises a lever pivotally mounted on said switch block.
